DRILLING BIT

Ole K. Olsen, Garland, Tex.

Application March 9, 1954, Serial No. 29,434

Term of patent 14 years

(Cl. D54—13)

Fig. 1

Fig. 2

Figure 1 is a side elevational view of a drilling bit showing my new design; and

Figure 2 is a top plan view thereof.

The dominant feature of this drilling bit is an extended vertical lateral portion of the blade and the large angular space between the blades, with the faces of the blades intersecting uniformly at the longitudinal axis of the bit together with the uniform stepped lower ends of the blades and the curved upwardly sloping shoulders behind each step of the blades.

I claim:

The ornamental design for a drilling bit, substantially as shown and described.
